PREPARATION HAVING ENHANCED SEXUAL HORMONE ACTION AND PROCESS OF MAKING SAME

Karl Miescher, Riehen, and Albert Wettstein, Basel, Switzerland, assignors to the firm of Society of Chemical Industry in Basle, Basel, Switzerland

No Drawing. Application February 10, 1937, Serial No. 125,122. In Switzerland February 25, 1936

4 Claims. (Cl. 167—74)

This invention relates to the manufacture of preparations for parenteral use having enhanced sexual hormone action by combining sexual hormones or their derivatives with a compound containing a carboxylic hydroxyl, an alcoholic hydroxyl or a carbonyl group, such as carboxylic acids, mono- or dihydric alcohols, ketones or aldehydes. Both saturated compounds and compounds containing double or treble linkings have proved effective.

The following table shows the effect of such activators on, for example, the action of the testosterone on young castrated rats (the weight of a rat at the time of castration was 60 to 80 grams; the experiment began 30 days after the castration). The animals received during 10 days daily each a subcutaneous injection of 50 γ of testosterone and the stated quantity of the compound named dissolved in 0.5 cc. of sesame oil. On the 11th day they were examined.

stene-dione, methyl-testosterone or the like, as follows for example from the following table:

Compounds	Daily dose γ	Without palmitic acid, weight in mg.		With 50 mg. palmitic acid daily, weight in mg.		5 10 15 10
		Seminal vesicles	Prostates	Seminal vesicles	Prostates	
17-methyltestosterone	50	58	88	*160	*210	
17-ethyldihydrotestosterone	500	49	108	70	148	
	200	19	55	40	60	
Androstan-3-cis-17-trans-diol	200	74	140	239	308	
Androstan-3-trans-17-trans-diol	1000	48	71	114	136	15
	500	30	50	99	120	
Androstenedione	500	126	166	208	251	

*Values obtained with brassidic acid instead of palmitic acid.

Instead of sesame oil other oils or other solvents suitable for the parenteral introduction of medicaments or mixtures of such solvents may be used. Instead of the compounds listed above other substituted or unsubstituted carboxylic acids, mono- or divalent alcohols, ethers, ketones or aldehydes, particularly those of the aliphatic series but also those of a fatty aromatic nature, may be used alone or in combination with each other. Instead of the free acids their salts or esters with poly-alcohols or poly-oxy-ketones, these esters containing at least one free hydroxyl group, may be used, for instance the propane diol mono-palmitic acid ester, the glycerol mono- or di-palmitic acid ester or the like. The substituted compounds may contain one or more substituents of the same kind or of different kinds; thus oxy-acids, ketonic acids or esters thereof, oxy-aldehydes, oxy-ketones, di-aldehydes, di-ketones and ether alcohols are applicable.

The above named activators may also be used with female sexual hormones and their derivatives, for example oestrone, oestradiol and their esters as well as with progesterone.

Instead of the natural sexual hormones artificially made compounds of analogous action may be similarly used.

The new preparations are useful in therapeutics as sexual hormone preparations.

What we claim is:

1. Preparations for parenteral use having enhanced sexual hormone action, obtained by combining a sexual hormone selected from the group consisting of testosterone, androstan-diol, androstan-3-diol, 17-methyl-testosterone, oestrone, oestradiol and androstan-3-dione with a compound selected from the group consisting of aliphatic carboxylic acids, aliphatic hydroxy-carboxylic acids and aliphatic alcohols.

2. Preparations for parenteral use having enhanced male sexual hormone action, obtained by

Compounds	Formula	Daily dose in mg.	Weight in mg.		25 30 35 40 45 50 55
			Seminal vesicles	Prostates	
ω-hydroxy-tridecanoic acid	C ₁₃ H ₂₆ O ₃	10	132	124
